GASEOUS ELECTRIC DISCHARGE LAMP

Lyman B. Johnson, East Orange, N. J., assignor to
General Electric Vapor Lamp Company, Hoboken, N. J., a corporation of New Jersey

Application May 21, 1937, Serial No. 144,070

2 Claims. (Cl. 176—122)

The present invention relates to electric gaseous discharge lamps generally, and especially to lamps designed for use in optical systems and the like.

5 A particular object of the invention is to produce a lamp of the electric gaseous discharge type which will have a uniform light distribution in all directions about its axis. A further object of the invention is to provide a tubular lamp of 10 the single base type which will have this uniform light distribution characteristic. Still other objects and advantages of the invention will appear from the following detailed specification or from an inspection of the accompanying drawing.

15 The invention consists in the new and novel structure and combination of elements, as hereinafter set forth and claimed.

Where lamps are used in connection with optical systems and the like it is frequently desirable that the light emission therefrom should be uniform in all directions. This fact has created difficulties where lamps of the gaseous discharge type were used, due to the fact that these lamps generally involve the use of an elongated 25 arc path, with the necessity of making electrical connection to the electrodes at each end thereof. Thus wherever a straight tube with a base attached to a single end thereof is employed it is necessary to bring one of the electrical leads 30 back along the length of the envelope to this base. This lead obviously obstructs the light from the lamp, and while this obstruction is so small in amount as to be of no practical importance for general lighting purposes, it is sufficient to 35 produce objectionable asymmetry in the light provided for use in optical systems, such as those used for projection, for example, especially where the light source is of high intrinsic brightness. I have now found that this difficulty is entirely 40 eliminated by the use of a return lead of novel shape. According to my invention this lead follows a helical path about the lamp envelope, and preferably out of contact therewith, and is 45 without light obstructing supports along the path of the discharge. While this helical lead still results in some obstruction of the light, this obstruction is uniform in every direction, and hence is no longer a source of asymmetry, a perfectly uniformly lighted field being obtainable 50 with the inlead disposed in this novel manner about the discharge path.

For the purpose of illustrating my invention I have shown a preferred embodiment thereof in the accompanying drawing in which

55 Fig. 1 is an elevational view of an electric

gaseous discharge lamp of the high intrinsic brilliancy type which is now on the market, with its lead structure modified in accordance with my invention, and

Fig. 2 is a sectional view of the same lamp taken 5 on the line 2—2 of Fig. 1.

As shown in these figures my novel lamp has a sealed envelope 1 of glass or the like to which a conventional base 2 is attached in the usual manner at the lower end. This envelope is preferably clear in order not to lose the optical advantage of the concentrated high intrinsic brilliancy light source which is housed therein. Through the reentrant pinch seal 3 of said envelope there extend a pair of inleads 4 and 5 which are connected externally to said envelope with the tip and sleeve of the base 2 in a usual manner. Centrally disposed within said envelope 1 is a tubular capillary lamp, of a type which is now well known, having a quartz envelope 6 20 into opposite ends of which are sealed inleads 7 and 8 through long beaded seals. These inleads terminate within suitable electrode chambers at each end of said envelope 6, where they support activated thermionic cathodes 9 of the 25 self-heating type. The envelope 6 contains a suitable filling, as of argon and mercury, but since the details of the structure of this lamp form no part of the present invention they will not be further discussed here. The inlead 4 30 extends up past the lower seal of the envelope 6 and has a metal strip 10 welded thereto which passes around the beaded seal and thus affords support for said envelope 6. Electrical connection between said inlead 4 and the inlead 8 is 35 provided by means of a flexible stranded conductor 11. The other inlead 5 extends upwardly to a point opposite the lower cathode 9, where it has welded thereto a metal strip 12 which encircles the adjacent electrode chamber of the 40 envelope 6, thus affording further support for said envelope, and also providing an external electrode which materially decreases the voltage required to initiate a discharge between the electrodes 9. A helix 13 of say 20 mil wire, of 45 tungsten, molybdenum, nickel or other suitable metal has one end welded to the inlead 5 near the end thereof and extends along the envelope 6 and co-axially therewith to a point beyond the upper cathode 9, where it encircles the upper beaded 50 seal with several smaller turns 14 and then has its end welded to a spring support 15 which is in the form of a ring which extended curved ends bearing against the inner surface of the envelope 1. This construction obviously affords mechan- 55

ical support for the upper end of the envelope 6 against lateral displacement. Hence it is unnecessary for the helix 13 to have rigidity beyond that necessary to maintain its own form, 5 so that it can be made of relatively fine wire. This helix is preferably made of considerably larger diameter than that of the envelope 6, so that it will not tend to produce sharp shadows from the highly constricted light source. It is 10 furthermore desirable that there should be a whole number of turns of said helix about the light emitting portion of the envelope 6, between the electrodes 9, so that the light obstruction by said helix will be identical in every direction 15 about the axis of the lamp. Electrical connection is established between the helix 13 and the inlead 7 by means of the short flexible conductor 16 of stranded wire.

Upon connection of this lamp to a suitable 20 source of electrical energy through the customary ballasting impedance a discharge is initiated between the cathodes 9 which is highly constricted and of extremely high intrinsic brilliancy. The light from this discharge is very effective, due to 25 this high brilliancy and the relatively small area of the source, for use with optical systems, especially in view of the novel use of the low resistance helical lead 13, whereby the production of asymmetrical shadows is avoided, and uniform 30 illumination of all points about the axis obtained.

While I have described my invention by reference to a specific embodiment thereof, it is to be understood that it is not limited thereto, but that

various changes, omissions and substitutions, within the scope of the appended claims, may be made therein without departing from the spirit of the invention.

I claim as my invention:

1. A lamp of the gaseous electric discharge type comprising a tubular sealed envelope containing a gaseous atmosphere and having electrodes sealed therein adjacent opposite ends thereof with a constricted arc path between said 10 electrodes to provide a light source of high intrinsic brilliancy, a supporting base adjacent one end of said envelope and having a pair of leads, one of said leads being connected to the adjacent electrode of said lamp while the other of said leads 15 extends helically about said envelope without light obstructing supports to a point beyond the discharge path, and with a whole number of turns opposite said discharge path, to make a connection with the other electrode, whereby the 20 shadow cast by the latter lead is symmetrical about the axis of said envelope.

2. An electric lamp comprising a sealed envelope, means to conduct an electrical current along a line path between two terminals therein 25 to produce light radiations, and a pair of electrical leads to said terminals, one of said leads extending in the shape of a coaxial helix about said line path with a plurality of whole turns interposed between said terminals, whereby the 30 light distribution from said line path is substantially uniform in all directions.

LYMAN B. JOHNSON.
